UNITED STATES PATENT OFFICE.

SANTIAGO ARCE, OF BUENOS AIRES, ARGENTINA.

SPEED-TRANSFORMER.

1,271,828.

Specification of Letters Patent.

Patented July 9, 1918.

Application filed June 27, 1917. Serial No. 177,291.

To all whom it may concern:

Be it known that I, SANTIAGO ARCE, citizen of the Argentine Republic, residing at No. 942 Brazil street, Buenos Aires, Argentina, have invented certain new and useful 5 Improvements in Speed-Transformers, of which the following is a specification.

The present invention has reference to transmission mechanism; and it comprises, 10 briefly, the provision of an improved mechanism of the general class or character specified which may be utilized as a direct coupling between motors, engines and other prime movers, and driven machinery of any 15 character.

According to the invention, the improved transmission mechanism provides for an unlimited range of high and low speeds, while constantly keeping the motor at the most 20 economical or effective speed, as well as permitting reversal of motion to be brought about readily and quickly and by means of simple, easily-operated controlling means, irrespective of the type of engine or motor, 25 or of the machinery to be driven. Also, the improved mechanism is susceptible of being employed in industrial plants for direct coupling of high-speed engines, thereby facilitating the use therein of turbines, electric 30 engines and centrifugal apparatus. The mechanism further enables direct coupling and change of speed to be performed without interruption of operation, and in this connection is designed as a substitute for the 35 differentials ordinarily used, particularly motor car brakes and clutch brakes, which also serve to control the speed, and the reversing gear, all of the operations effected by those parts being accomplished by the im- 40 proved mechanism of the invention. Other and further objects and advantages will appear as the description proceeds.

A structural embodiment of the invention is illustrated in the accompanying drawing, 45 wherein:

Figure 1 is a central, longitudinal sectional view, with parts in elevation, showing the invention in use.

Fig. 2 is a transverse, vertical section, 50 taken on line 2—2, Fig. 3.

Fig. 3 is a side elevation of the structure shown in section in Fig. 1.

Fig. 4 is a fragmental, vertical sectional view, showing a modification.

Fig. 5 is a vertical sectional view, show-

ing a plurality of transmission devices coupled together in tandem.

Referring more particularly to said drawing, 6 and 7 indicate the two main shafts comprised in the apparatus and connected, 60 respectively, with the motor, engine or other prime mover 8 and the machinery or work 9 to be driven. The shaft 6 may either be coupled directly to, or may itself constitute the motor shaft; and, similarly, the shaft 7 65 may either be coupled to, or may constitute, the main shaft of the driven machinery or work. In any case, however, the two shafts are arranged in endwise alinement, with a small space between their confronting ends 70 wherein a set of anti-friction bearings 10 is disposed, said bearings being indicated diagrammatically in Fig. 1; and to prevent endwise shifting, said shafts are respectively provided with collars 11 and 12. 75

The driven shaft 7 has keyed to its inner end a gear 13, (Figs. 1 and 2), which meshes with one or more gears 14, carried by and located between a pair of disks 15. In the construction illustrated, three of these gears 80 14, spaced at equal distances apart are shown, said gears being rotatably mounted on horizontal connecting crank pins 16, the ends of which are fitted in openings formed in said disks. The crank disks 15 are formed 85 with extended or relatively-long hubs 17, which project away from each other in opposite directions. The hub on the right-hand crank disk fits loosely or rotatably over the inner end portion of the driven shaft 7 90 and terminates adjacent the collar 12; while the hub on the left-hand crank disk projects beyond the free end of said shaft, bridges the space between the latter and the driving shaft 6 and extends a slight distance across 95 the free end of said driving shaft, as represented in Fig. 1.

The three gears 14 mesh with an external annular gear or gear ring 18 (best shown in Fig. 2) fixed to the peripheral wall of the 100 central section or member 19 of a cylindrical case, which incloses the afore-mentioned gears and disks and comprises, in addition to the central section 19, left- and right-hand sections 20 and 21, the three sections 105 19, 20 and 21 being bolted or otherwise suitably fastened together. The central section 19 is turned inwardly at its opposite sides, and these in-turned portions, which are indicated at 22 in Fig. 1, encircle the 110

crank disk hubs 17 and have a relative rotary movement with respect thereto, the confronting faces of the parts 22 and 17 having anti-friction bearings 23 interposed between them. The left- and right-hand sections are substantially annular, and are so formed as to serve as clutch members, for co-operation with a pair of shiftable clutch members 24 and 25 disposed, respectively, to left and right of the case. The end portions of the crank disk hubs 17 project outwardly beyond the side walls 22 of the case and are equipped with disk-like enlargements 26 and 27, which are also constructed to function as clutches. The left-hand, annular section 20 has its inner wall beveled or inclined to form a clutch face, and the disk 26 adjacent thereto also has a beveled edge face, the two beveled faces being co-axial and parallel with each other and disposed in spaced relation. The right-hand section 21 has a much greater width than the section 20, and its inner portion is cylindrical, as shown, its outer portion 28 being tapered or made frusto-conical to provide an internal clutch face, which is co-axial with the beveled edge face of the right-hand disk 27 and is disposed in spaced, parallel relation thereto.

30 The shiftable clutch members 24 and 25 are provided at their inner ends with frusto-conical, annular projections or tongues 29 and 30, which are introduced into the spaces between the clutch faces of the parts 20 and 26, and of the parts 28 and 27, respectively; these spaces being of sufficient width to enable a lateral or sliding movement of the clutch tongues therein which will bring said tongues into frictional engagement with either face alternatively or permit them to remain out of engagement with both faces, according as may be desired. The left-hand clutch member 24 is keyed to the drive shaft 6 to rotate therewith, and is shifted laterally in one direction or the other by a two-armed lever 31 fulcrumed at the intersection of its arms at 32 on a fixed support or bearing 33, the lower arm of the lever being fastened to a yoke or ring 34 which encircles the clutch. The right-hand clutch member 25 is mounted on the driven shaft 7, but is capable of a lateral shifting movement only, being held against rotation by means of a pin or rod 35, which is fastened to the driven machinery 9 and projects loosely through an opening 36 formed through said clutch member. The shifting movements of this clutch member 25 are effected by a two-armed lever 37, which is suitably fastened thereto at its lower end at 40 and is fulcrumed at 38 on a fixed support or bearing 39. The first-named clutch member is directly operated by hand, as will be apparent from the foregoing; but the second, or right-hand clutch member, instead of being op-

erated in a similar manner, is connected with the first or main clutch in such a way that actuation of the lever 31 will produce a movement of both clutches simultaneously, the first clutch acting to couple the engine 70 for either forward or reverse movement, and the second clutch acting to couple the work and vary the speed at which the driven shaft is rotated. According to the construction shown, the connection between the two levers 75 31 and 37 comprises a pair of rods 41 and 42 which cross each other intermediate their ends and are pivoted at their front ends to the lever 31 at opposite sides of its fulcrum 32, the rear ends of said rods acting against 80 a pair of expandable controlling springs 43 and 44, which are connected to the lever 37 at opposite sides of its fulcrum 38.

In addition to the parts above described, the improved transmission mechanism embodies a pair of pedals 45 and 46, both of which are connected to control the slidable, non-rotatable rear clutch 25. These pedals 45 and 46 are fulcrumed at 47 and 48 on fixed supports or bearings 49 and 50, respectively, and are connected with the lever 37 below and above its fulcrum 38 by rods 51 and 52, which are rigid or non-yielding, in contradistinction to the spring-pressed rods 41 and 42.

The operation, so far as the above description is concerned, is substantially as follows:—The hand lever 31, which directly controls the main clutch 24, has three definite positions, corresponding to neutral, forward and reverse. When in the first position, the main clutch 24 is uncoupled both from the clutch disk 26 and from the casing clutch ring 20, and the secondary or auxiliary clutch 25 is similarly uncoupled from both companion clutches 27 and 28. To produce a forward rotary movement of the work, the said lever 31 is pulled back from its neutral position into the position represented in Fig. 1, during which time the main 100 clutch is shifted forwardly, (to the left in Fig. 1), thereby bringing the inner face of its clutch portion 29 into frictional engagement with the face of the clutch disk 26. This operation connects the power drive 110 with the crank disks 15 which carry the planet gears 14, and said crank disks, and hence the said gears 14, are positively and directly driven from the drive shaft 6. At the same time that the main clutch 24 is 120 shifted in the manner just described, the secondary clutch 25 is shifted to the right, (Fig. 1), so that its clutch portion 30 is engaged with the clutch face 28 on the right-hand section 21 of the case. Consequently, 125 since the said clutch 25 is incapable of rotating, its engagement with the case will lock the latter, and with it the gear ring 18 against rotation, and the rotary driving movement of the planet gears will be trans- 130

mitted directly to the central gear 13, which is keyed to the driven shaft 7 as previously stated, with the result that the said gear 13 and shaft 7 will be positively and constantly 5 rotated at a definite speed which is proportionately greater than that of the drive shaft 6.

This speed may, however, be variably reduced by actuation of the pedal 45, such 10 actuation producing a forward movement of the non-rotatable secondary clutch 25, with a resultant slippage between the parts 30 and 28 and, consequently, a corresponding slippage between the planet gears 14 15 and the ring gear 18. The movement of the lever 37, effected by the actuation of said pedal 45, entails no resultant movement of the main clutch 24 which remains in action, because of the yielding connections provided 20 by the springs 43 and 44. Stoppage may be readily effected whenever desired by simply depressing said pedal far enough to first disengage the parts 30 and 28 and then engage the said part 30 with the right-hand clutch 25 disk 27, thereby braking the two crank disks 15 and terminating the rotation of the central gear 13 even though the main clutch remains in active position. To abruptly stop the machine, it is necessary merely to 30 move lever 31 forward to neutral position and then to fully depress pedal 45, the movement of the lever effecting simultaneous uncoupling of the two clutches, while the subsequent movement of the pedal 35 brings the secondary or stationary clutch into engagement with the right-hand crank disk 27 with the result just stated.

Reversal of the direction of rotation is effected by moving lever 31 forward from 40 its intermediate or neutral position, such movement causing a rearward movement of the main clutch 24 and a forward movement of the secondary clutch 25. The first-named clutch is thereby brought into binding 45 engagement with the clutch face of the annular casing member 20, while the other clutch is engaged with that of the adjacent clutch disk 27, which latter, it will be recalled, is connected with one of the two 50 crank disks 15 that carry the planet gears 14. It follows, therefore, that the motor is connected to directly and positively drive the ring gear 18, while at the same time the crank disks are locked against rotation and, 55 in turn, hold the planet gears against traveling movement. The power drive is thus transmitted from the motor and the drive shaft 6 to the ring gear 18, and thence through the planet gears to the central gear 60 13 on the driven shaft 7, the latter turning in the opposite direction from that when the crank disks are driven. By depressing the other pedal 46, the speed at which the driven shaft is now being rotated may be 65 varied as desired, just as is possible in the

case of forward drive by actuating the pedal 45;—that is to say, the clutch part 30 of the secondary clutch may be loosened from its binding engagement with the clutch disk 27, so as to permit slippage therebetween, 70 the speed decreasing as the amount of slippage increases, and vice versa. Stoppage may be effected as in the first case, by moving lever 31 to neutral position and then setting up a braking action, in this instance by 75 depressing pedal 46 and thereby shifting the non-rotating, secondary clutch into engagement with the clutch part 28; and may also be effected, as in the first case, by actuating pedal 46 to first disengage the clutch parts 80 30 and 27 from each other and then engage the former with the part 28.

It will be seen from the foregoing that the two pedals 45 and 46 serve to control the variation in speed, since they determine 85 the amount of slippage between the clutch part 30 of the non-rotatable brake clutch 25 and the clutch parts 27 and 28, as has been explained. The same result may be obtained, moreover, with a three-position hand 90 lever, which, accordingly, might be used in place of the pedals, as will be apparent. The control lever 31 may be used to effect either direct or reverse drive, as likewise explained above; but before reversing, it is 95 advisable to depress the pedal 46, in order to commence the movement by degrees.

When it is desired to run, with the motor uncoupled, utilizing the momentum of the moving parts, this can be effected by moving 100 the lever 31 to neutral position, thereby disengaging both clutches, as previously explained; but the speed should be periodically decreased by depressing one or the other of the pedals, according to the direction 105 in which the driven shaft is turning.

While none of the operations above described entails any risk of injuring either the engine or the transmission device, provided due care is observed, since the parts 110 of the transmission render the motor almost automatically independent of the driven shaft, and since the combined operation of the main and secondary clutches 24 and 25, effected by moving lever 31 from its rear to 115 its front position, or vice versa, always applies the brakes automatically before coupling the motor, it is nevertheless advisable to make use of the usual brake that acts directly on the wheels, so as to avoid the 120 imposition of excessive strains on the parts mounted on the driven shaft.

In case the invention is to be applied to machinery having a constant speed, its construction can be materially simplified by 125 omitting both the main and secondary clutch parts 24 and 25, and directly coupling the left-hand clutch disk 26 in some suitable manner to the drive shaft 6, or its equivalent, while at the same time securing 130

the ring gear 18 and its case against motion. The parts carried by the driven shaft will then act solely as a transmission device and will exert no braking action whatever, 5 the said device serving to multiply the speed of the driven shaft with relation to that of the drive shaft. On the other hand, where it is desired to couple a motor or engine having a constant speed to variable-speed 10 machinery, or vice versa, then the main clutch part 24 may be omitted as before, but the secondary clutch part 25 will be retained, and a centrifugal regulator or governor 53 may be interposed between the right-hand 15 clutch disk 27', which is slightly modified, and the said clutch 25 and connected to the latter, as represented in Fig. 4. In such case, the spring 54 associated with the governor will normally hold the clutch parts 30 and 28 20 engaged; but when the speed at which the driven shaft is being rotated becomes excessive, then the weighted arms of the governor, by flying outward, will pull the clutch 25 bodily to the left, thereby disrupting 25 the engagement between the said parts 30 and 28 and, if the driven shaft has attained a dangerously high speed, will ultimately bring the clutch 25 into engagement with the disk 27'.

30 Finally, it is possible in any case to couple together a plurality of the transmission devices together in tandem, where either high-speed or low-speed machines are to be run, an arrangement of this character being 35 illustrated in Fig. 5, which shows three of said devices coupled together. In connecting up the parts according to this arrangement, the central gear 13 of each device is keyed to the corresponding shaft section 40 and, in addition, the left-hand crank disk 15 of each device also has a key mounting on its shaft section, so that one crank disk of each succeeding device is keyed to one 45 shaft section, while the other crank disk is loose on the next section, the latter sector also having the central gear of the device keyed thereon. The case is held against rotation in any suitable manner, and either end shaft section may be positively driven 50 from the motor or other source of power, according as the speed is to be multiplied or reduced. In the construction illustrated, assuming that the left-hand shaft section 6' is the driving element, then power is transmitted 55 from that section through the crank disk 15 thereon and the planet gears carried by said disk to the central gear 13 on the next section to the right 6'; thence in the same way through the left-hand crank disk of the 60 second device to the third shaft section 6'; and finally from said shaft section 6' to the fourth or right-hand shaft section 6''. The reverse takes place when the last-named 65 shaft section 6'' constitutes the driving part, with the difference, however, that the speed

of the driven section 6' is greatly reduced, instead of increased, as compared with that of the driving section.

While the preferred embodiment of the invention has been illustrated, it is to be understood that no limitation to the precise structural details thereof is contemplated. On the contrary, the invention is susceptible of substantial modification and change in the size, proportions and relative arrangement of its component parts within its scope as prescribed by the appended claims. 75

I claim as my invention:—

1. In a variable speed transmission, the combination, with a drive shaft and a driven shaft arranged in endwise alinement; of a gear fixed to the driven shaft; a planet gear in mesh therewith; a crank disk carrying said planet gear and loosely mounted on said driven shaft; a ring gear encircling said gears and meshing with the planet gear; means for coupling the drive shaft to either said crank disk or said ring gear to positively rotate the same; and means for simultaneously locking the uncoupled one of said elements in relatively-fixed position. 80

2. In a variable speed transmission, the combination, with a drive shaft and a driven shaft arranged in endwise alinement; of a gear fixed to the driven shaft; a planet gear in mesh therewith; a crank disk carrying said planet gear and loosely mounted on said driven shaft; a ring gear encircling said gears and meshing with the planet gear; a rotatable case to which said ring gear is internally affixed, said case and said crank disk each having a clutch member connected thereto; and a member keyed to said drive shaft and having a clutch portion intermediate said clutch members to selectively engage either of them, to transmit the movement of said drive shaft either to said crank disk or to said ring gear. 95

3. In a variable speed transmission, the combination, with a drive shaft and a driven shaft arranged in endwise alinement; of a gear fixed to the driven shaft; a set of planet gears in mesh therewith; a crank disk carrying said planet gears and loosely mounted on said driven shaft; a ring gear disposed externally of said planet gears and meshing with the same; and means whereby the coupling of the drive shaft to positively rotate either the crank-disk or the ring gear automatically locks the uncoupled one of said elements in relatively-fixed position. 110

4. In a variable speed transmission, the combination, with a drive shaft and a driven shaft arranged in endwise alinement; of a gear fixed to the driven shaft; a planet gear in mesh therewith; a crank disk carrying said planet gear and loosely mounted on said driven shaft; a ring gear encircling said gears and meshing with the planet gear; a rotatable case to which said ring gear is in- 115

120 125 130

- ternally affixed, said case and said crank disk each having a clutch member connected thereto; a clutch keyed to the drive shaft to selectively engage either of said clutch members; a brake operative selectively upon said ring gear and said crank disk; and means for simultaneously operating said clutch and applying said brake, to positively drive either said crank disk or said ring gear and lock the other in relatively-fixed position. 5
5. In a variable speed transmission, the combination, with a drive shaft and a driven shaft arranged in endwise alinement; of a gear fixed to the driven shaft; a planet gear in mesh therewith; a carrier for the planet gear loose on said driven shaft; a ring gear encircling said gears and meshing with the planet gear; means for coupling said drive shaft to either said carrier or said ring gear to positively rotate the same; a brake for holding the uncoupled one of said elements in relatively-fixed position; and applying means for operating said coupling means and said brake simultaneously. 10
- 20 6. In a variable speed transmission, the combination, with a drive shaft and a driven shaft arranged in endwise alinement; of a gear fixed to the driven shaft; a planet gear in mesh therewith; a carrier for the planet gear loose on said driven shaft; a ring gear encircling said gears and meshing with the planet gear; means for coupling said drive shaft to either said carrier or said ring gear to positively rotate the same; a brake for holding the uncoupled one of said elements in relatively-fixed position; and means associated with the brake for effecting variable slippage between said brake and said uncoupled element. 25
- 30 7. In a variable speed transmission, the combination, with a drive shaft and a driven shaft arranged in endwise alinement; of a gear fixed to the driven shaft; a planet gear in mesh therewith; a carrier for the planet gear loose on said driven shaft; a ring gear encircling said gears and meshing with the planet gear; means for coupling said drive shaft to either said carrier or said ring gear to positively rotate the same; a brake for holding the uncoupled one of said elements in relatively-fixed position; means for operating said coupling means and applying said brake simultaneously; and means associated with the brake for effecting variable slippage between said brake and said uncoupled element. 35
- 40 8. In a variable speed transmission, the combination, with a drive shaft and a driven shaft arranged in endwise alinement; of a gear fixed to the driven shaft; a planet gear in mesh therewith; a carrier for the planet gear loose on said driven shaft; a ring gear encircling said gears and meshing with the planet gear; means for coupling said drive shaft to either said carrier or said ring gear to positively rotate the same; a brake for holding the uncoupled one of said elements in relatively-fixed position; means for operating said coupling means and applying said brake simultaneously; and means associated with the brake for effecting variable slippage between said brake and said uncoupled element. 45
- 50 9. In a variable speed transmission, the combination, with a drive shaft and a driven shaft arranged in endwise alinement; of a gear fixed to the driven shaft; a planet gear in mesh therewith; a carrier for the planet gear loose on said driven shaft; a ring gear encircling said gears and meshing with the planet gear; means for coupling said drive shaft to either said carrier or said ring gear to positively rotate the same; a brake for holding the uncoupled one of said elements in relatively-fixed position; and means connected with said brake to variably release it from said uncoupled gear so as to cause 55 variable slippage between the latter and the brake. 70
- 10 9. In a variable speed transmission, the combination, with a drive shaft and a driven shaft; of a transmission gear system mounted on the driven shaft and including a member fixed thereto; means for coupling the drive shaft to said gear system to positively rotate the same; a brake operative upon said gear system; and means connected to operate said coupling means and apply said brake simultaneously. 75
- 15 10. In a variable speed transmission, the combination, with a drive shaft and a driven shaft; of a transmission gear system mounted on the driven shaft and including a member fixed thereto; means for coupling the drive shaft to said gear system to positively rotate the same; a brake operative upon said gear system; a lever connected to operate 80 said coupling means and apply said brake simultaneously; and a pair of pedals connected to shift said brake alternatively in one direction or the other independently of said lever. 85
- 20 11. In a variable speed transmission, the combination, with a drive shaft and a driven shaft; of a transmission gear system mounted on the driven shaft and including a member fixed thereto; means for coupling the drive shaft to said gear system to positively rotate the same; a shiftable, non-rotatable brake engageable with said gear system; and means for applying said brake and said coupling means simultaneously. 90
- 25 12. In a variable speed transmission, the combination, with a drive shaft and a driven shaft; of a transmission gear system mounted on the driven shaft and including a member fixed thereto; a clutch keyed to the drive shaft to rotate therewith; a non-rotatable clutch slidably mounted on said driven shaft, both clutches being movable into and out of engagement with said gear system; and means for operating both 100 clutches simultaneously. 105
- 30 13. In a variable speed transmission, the combination, with a drive shaft and a driven shaft; of a transmission gear system mounted on the driven shaft and including a member fixed thereto; a clutch keyed to the drive shaft to rotate therewith; a non-rotatable clutch slidably mounted on said driven shaft, both clutches being movable into and out of engagement with said gear system; means for operating both clutches simultaneously; and means for operating the non-rotatable clutch independently of the first-named operating means. 110
- 35 14. In a variable speed transmission, the 120
- 40 15. In a variable speed transmission, the 125
- 45 16. In a variable speed transmission, the 130

to assume a position out of engagement with both of them; and means for effecting slippage between said brake and the part acted upon by it, to vary the speed of the driven shaft.

22. In a variable speed transmission, the combination, with a drive shaft and a driven shaft; of a planetary gear system mounted on the driven shaft and comprising a central gear fixed to said driven shaft, a planet gear in mesh therewith and an external gear encircling said central and planet gears; a pair of concentric, annular clutch members disposed in spaced relation and connected one to the external gear and the other to the planet gear; a shiftable member keyed to the drive shaft to rotate therewith and hav-

ing an annular clutch portion extending into the space between the first-named clutch members to engage one or the other 20 of them or to assume a position out of engagement with both of them; means for operating said shiftable clutch member and said brake simultaneously; and means for effecting slippage between said brake and 25 the part acted upon by it, to vary the speed of the driven shaft.

In testimony whereof I affix my signature in presence of two witnesses.

SANTIAGO ARCE.
